United States Patent Office.

WILLIAM A. FIELD, OF BOSTON, MASSACHUSETTS.

Letters Patent No. 63,876, dated April 16, 1867.

IMPROVED BLACKING-BOX HOLDER.

The Schedule referred to in these Letters Patent and making part of the same.

TO ALL PERSONS TO WHOM THESE PRESENTS SHALL COME:

Be it known that I, WILLIAM A. FIELD, of Boston, in the county of Suffolk, and State of Massachusetts, have invented an improved Blacking-Box Holder, and do hereby declare the same to be fully described in the following specification, and represented in the accompanying drawings, of which—

Figure 1 is a top view; and

Figure 2 a vertical and longitudinal section of it.

The blacking-box holder is a round and shallow box, A, provided with a handle, *a*, to project from its circumference, and also with a cover, *b*, to turn laterally on and off the box, and on a wood screw, *c*, going through the cover and into the box near the edge of the latter, the form and arrangement of the box, the cover, and the screw being as represented in the drawing. On the handle, and close to its junction with the box, I affix, by means of a screw, *d*, a block, *e*, of vulcanized India rubber, it being so arranged as to project a little into the path of movement of the cover, or to press against the periphery of the cover, in order to hold such cover closed, and to allow it to be easily moved aside on the box, as occasion may require. Thus the cover will be held closely by means of an elastic or a friction and pressure fastening. For securing a blacking-box, B, within the holder I employ a screw, *f*, to screw laterally through the circumference of the holder A, and against the box B. Such screw *f*, being formed with a head, *g*, serves the purpose of enabling a person to revolve the screw. Its eye or hole, *h*, answers to enable the blacking-box holder to be hung upon a hook or nail inserted in a wall or post. The arrangement of the screw relatively to the handle and cover is such as to be advantageous, as the screw, by such, serves as a means not merely of fastening the blacking-box in place in the holder, but it also serves to suspend the holder from a hook or nail, and to bring the cover into a position by which its gravity or weight will aid in closing or keeping it closed when the holder is so suspended.

What I claim as my invention or improvement is as follows:

I claim the combination of devices constituting my improved blacking-box holder, viz, the box A, its handle *a*, cover *b*, elastic block *e*, and screw *f*, arranged substantially as specified.

WILLIAM A. FIELD.
